DESIGN FOR A CARRIAGE HOOD

Samuel Kroll and Nathan J. Kroll, Chicago, Ill.

Application May 22, 1944, Serial No. 113,707

Term of patent 7 years

(Cl. D14—27)

To all whom it may concern:

Be it known that we, Samuel Kroll and Nathan J. Kroll, both citizens of the United States and both residents of Chicago, in the county of Cook and State of Illinois, have invented a new, original, and ornamental Design for a Carriage Hood, of which the following is a specification, reference being had to the accompanying drawing, forming a part thereof, and in which:

Fig. 1 is a perspective view of the carriage hood showing our new design;

Fig. 2 is a top plan view of the same, at a slightly larger scale;

Fig. 3 is a profile view of the covering taken substantially on line 3—3 of Fig. 2; and

Fig. 4 is an enlarged fragmentary view illustrating a portion of the carriage hood material used in our new design.

We claim:

The ornamental design for a carriage hood, as shown and described.

SAMUEL KROLL,
NATHAN J. KROLL.
